UNITED STATES PATENT OFFICE.

GEORGE WALDEMAR BUNGAY, OF BROOKLYN, NEW YORK, ASSIGNOR TO ACME DIE CASTING CORPORATION, A CORPORATION OF NEW YORK.

CONTROL-BOX.

1,309,611.

Specification of Letters Patent. Patented July 15, 1919.

Application filed August 30, 1916. Serial No. 117,596.

To all whom it may concern:

Be it known that I, GEORGE WALDEMAR BUNGAY, a citizen of the United States, residing at the borough of Brooklyn, in the 5 county of Kings and State of New York, have invented certain new and useful Improvements in Control-Boxes, of which the following is a specification, reference being had therein to the accompanying drawings, 10 forming part thereof.

My present invention relates to an improved form of controller for use in connection with apparatus actuated by steam or other elastic fluid under pressure. My improved controller is useful in connection with any apparatus wherein a plurality of steam pistons or equivalent devices are employed to actuate or impel different parts or elements of such apparatus in a given order; 15 and the principal object and function of my improvement is to provide means whereby the requisite movements of such steam pistons, etc., may be produced with certainty in their proper order. My improved controller makes it possible to attain these ends by the simplest possible manual operation, and without any risk or accident due to 20 careless or inattentive operation.

While my improvement, as claimed, is 25 capable of application to any of the great variety of devices, made as above characterized, the particular embodiment of my invention herein shown and described is especially adapted to be used in governing 30 or controlling the operation of a steam actuated die casting machine of the kind shown, described and claimed in my co-pending application for patent filed October 5, 1915, Serial No. 54,123, and which became 35 Patent No. 1,279,249, dated September 17, 1918. This die casting machine embodies two steam pistons, each double acting; that is to say, each being adapted to be positively moved in either direction by 40 steam (or its equivalent) entering at one end or the other of the cylinder within which the piston moves. One of these pistons acts in one direction to close the mold and place it in connection with the conduit 45 through which the molten metal is delivered, while movement of said piston in the opposite direction opens the mold and discharges the molded article. The second piston acts, when moving in one direction, 50 to force molten metal into the closed mold; 55

and, when the steam is reversed with respect to this second piston, the same is lifted into a position of idleness, awaiting the next operation.

It will be clear that each end of each steam cylinder must be capable of receiving and discharging the working fluid, and in my said pending application the inlet and exhaust of each end of each cylinder are controlled by rotary valves close to their respective cylinder ends. Appropriate successive action of these valves is produced by a specially constructed safety controller-handle, connected mechanically to two rocking shafts at opposite ends of the machine. Manipulation of the controller handle is somewhat complicated, and means are provided for preventing any accidental or careless movement of such controller which might result in operating the various parts of the machine in improper order.

By the use of my present invention, the moving arms, rods and shafts employed to convey movement to the four separate valves are done away with, and the control of the working fluid is accomplished within a single controller box governed by a single swinging handle, whence pipes convey the fluid to and from the two ends of the two cylinders.

The special embodiment of my invention above referred to is illustrated in the accompanying drawings, wherein Figure 1 is a side elevation of my controller box with one-half of the side removed, the better to show the interior; Fig. 2 is a section of the same on the line 2-2 in Fig. 1; Fig. 3 is a section on the line 3-3 in Fig. 2; Fig. 4 is a section on the line 4-4 of Fig. 2; Fig. 5 is a section on the line 5-5 in Fig. 2; and Fig. 6 is a perspective view of a preferred arrangement of cams and their shaft.

I shall describe the apparatus herein illustrated in its application to my die casting machine aforesaid, and it is to be understood that this description merely exemplifies the possible embodiments of my invention.

The working parts of my improved controller are contained within an outer box or casing 10, which may be fastened in any desired position to the fire box or other part of my die casting apparatus, but preferably so that the working handle 11 stands upright. This casing is divided by the par-

tion 12 into a cam chamber and a valve and conduit chamber. The valve and conduit chamber is further divided as follows:

Looking into the valve and conduit chamber from the direction of the handle 11, as in Fig. 2, it will be seen that a portion of the upper right hand corner is divided off to form a steam inlet chamber 13 which extends unbroken from end to end of the outer casing, as shown in Fig. 3. Live steam is led to this inlet chamber through the pipe 14.

At the lower left hand side of the valve and conduit chamber is shown the exhaust chamber 15, which also extends unbroken the full length of the casing, as shown in Fig. 4. The exhaust steam leaves by the pipe 16.

The remainder of the space within the casing 10, above the partition 12, is divided by unbroken cross partitions 17, 18 and 19 to form four separate and distinct passages or pockets, which open at the top of each into the respective pipes 20, 21, 22 and 23. The four puppet valves 24, 25, 26 and 27 open into the common inlet chamber 13, and these valves therefore command inlet of steam into the four pipes 20, 21, 22 and 23 respectively, as will be clear from inspection of Figs. 1 and 3. These inlet valves are lifted in a manner hereinafter described by means of the lifting stems 28, and are held down to their seats both by steam pressure and by springs 29 bearing upon washers 30 fixed on said stems.

The exhaust returning from the pipes 20, 21, 22 and 23 is controlled by similar puppet valves shown at 31, 32, 33 and 34 respectively; and these exhaust valves are lifted by the stems 35 normally held down by springs 36, bearing upon the washers 37.

As has already been explained, the inlet and exhaust valves must be operated in pairs corresponding to the respective pipes 20 to 23, and the inlet valve for each pipe should be opened at the same moment that the exhaust valve for the other pipe of the pair is opened and vice versa. In order to accomplish this simultaneous movement of the members of each pair by compact and reliable means of a simple character, I prefer the following construction.

Midway between the parallel planes determined by the two sets of parallel valve stems, and running from end to end of the casing 10, I place a rotary cam shaft 38, operated by the exterior handle or crank 11. Placed parallel with the shaft 38, and symmetrically placed above the same and on opposite sides of the lower division of the casing 10 are two spindles 39 and 40 which afford bearings for the eight valve levers. Of these last named elements, the levers 41, 42, 43 and 44 are supported at their extremities by the respective cams 45, 46, 47 and 48 and

are adapted to thrust upward the respective inlet valves 20 to 27 by means of their stems 28, whose lower extremities bear upon said levers at points well back from their ends. These levers turn or swing upon the spindle 39, being kept properly spaced by the intermediate thimbles 49. The spindle 40 carries a similar set of parallel valve levers 50, 51, 52 and 53, whose ends bear upon the cams 54, 55, 56 and 57. These levers serve to control the respective exhaust valves 31, 32, 33 and 34. They are suitably spaced by means of the thimbles 58. One side of the end of each of the valve levers is cut away so that they may overlap and make contact with parallel cams beneath them, while permitting the valve stems to rest opposite each other in common transverse planes; thus preserving the symmetrical arrangement of the corresponding inlet and outlet valves in each pair. This is clearly shown in Figs. 2 and 5.

The number of pairs of valves and their corresponding leading-off pipes will depend upon the number of steam cylinders and pistons to be appropriately controlled in any given mechanism. I have herein shown four of each, corresponding to the two ends of the two cylinders employed in the die casting machine heretofore mentioned. In the discussion of the operation of my invention, therefore, the pipe 20 will be considered as leading off to the top of the cylinder whose piston closes and opens the mold, the pipe 21 as leading off to the bottom of the same; 100 while the pipes 22 and 23 lead off respectively to the top and bottom of the metal pumping cylinder.

In the specific arrangement of cams which I have illustrated in the drawings, I have provided for the necessary successive operations to be brought about by a single forward and backward movement of the handle 11, whereby rotation through a half circle is accomplished, first in one direction and then in the other. It will be seen that each pair of cams includes one short-faced or peaked cam and one long-faced or extended rounded cam; and that these are placed in diametrical opposition. Otherwise expressed, each of the cams 45, 55, 47 and 57 is provided with a valve-closing dwell, while each of the cams 54, 46, 56 and 48 is provided with both a valve-opening dwell and a valve-closing dwell of which the valve-opening dwell is the longer, whereby one of the valves of each pair will be held open while the other is kept closed and then will be kept closed while the other is opened and closed. This opposition results from the fact that, in any given position, the opening of an inlet valve into a given leading-off pipe must always correspond to a closing of the exhaust to the same pipe and vice versa. It will also be observed, in comparing the 130

successive pairs of cams that if a peaked cam acts upon the inlet valve in one pair, a rounded cam acts upon the inlet valve in the pair next it, and vice versa. This follows 5 from the requirements of the die-casting machine wherein the exigencies of operation call for preservation of open or closed position respectively in certain valves. This is made clear from the following detailed 10 discussion of the cycle of operations for which the specific apparatus herein illustrated is intended.

When the machine is idle, and in readiness for use, the mold is open and the metal 15 pumping plunger is raised. This condition is preserved by the normal position of the controller, when the line of contact with the valve levers will be as represented by the uppermost dotted line in Fig. 6. In this 20 position the inlet valves 24 and 27 are open, as are the exhaust valves 32 and 33. All the others are closed (see Figs. 3 and 6). Consequently steam is admitted to the top 25 of the mold-controlling piston, thus holding the mold open, and to the bottom of the pump piston, thus keeping the plunger idle.

The first operation is to close the mold, without operating the pump. To do this the handle is turned ninety degrees, or until 30 the line of contact is as represented by the middle dotted line in Fig. 6. The extended curve of the rounded long-faced cams 56 and 48 has preserved the original condition so far as to keep the valves 33 and 27 open; 35 and the closed position of the valves 26 and 34 is maintained by reason of the fact that the movement described does not, as yet, bring the peaked or short-faced cams 47 and 57 into action. In other words, the two 40 pairs of cams at the right in Fig. 6 preserve the original positions of the valves, which communicate with the pipes 22 and 23, leading to the top and bottom respectively of the pump piston. At the same time the 45 other two pairs of cams, governing the operation of the mold-controlling piston produce a complete change in their corresponding valves, and we now have the pipe 20 in communication with the exhaust, while the 50 pipe 21 receives a supply of live steam. Consequently the mold-controlling piston will be lifted, and the mold will be closed in position to receive the molten metal.

The next operation will be to pump the 55 metal into the mold. To do this the pump must be operated while the mold-controlling mechanism remains immobile. This is accomplished by completing the half circular movement of the handle 11, thus bringing 60 the line of contact into the position represented by the lowermost dotted line in Fig. 6. Inspection of that figure will show that the left hand set of pairs of cams maintains the valve relation produced in the position 65 last above explained, while a complete

change is produced in the pump controlling valves governed by the two pairs of cams at the right of Fig. 6. The result will be that steam will be admitted to the top of the pump piston, to force down the pump 70 plunger, while the closed position of the mold is firmly maintained by the steam pressure under the piston controlling the same.

When the mold is filled, the handle is sim- 75 ply brought back to its original position, reproducing the positions above described in reverse order, whereby the pump plunger is first lifted and kept lifted, and the mold is then opened.

80

In view of the fact that the valve-operating cams are made in symmetrical halves, the operating handle 11 may be moved in either direction, half way around and back again, or, if desired, it may be successively 85 moved through two half rotations in the same direction to make one complete rotation, in either direction. However, it has been found most convenient to move this handle through the front half of the circle, 90 half way around and back, and the valve-operating action of the cams hereinbefore described has reference to such movement of the handle 11.

It is not essential to my invention that the 95 cams be arranged for operation by the half-circular motions described, since it is obvious that a different movement might be employed. It is also clear that the cams in each pair might be made to work in constant 100 mutual opposition without setting them 180 degrees apart as shown; and in my claims this broader view of the "opposition" of the cams is meant, where that expression is employed.

105

The controlling means of my present invention has been embodied in the die-casting machine forming the subject of my co-pending application for patent Serial No. 163,406, filed April 20, 1917, which became 110 Patent No. 1,279,650, dated September 24, 1918.

It is obvious that various modifications may be made in the construction shown in the drawings and above particularly de- 115 scribed within the principle and scope of my invention.

I claim:

1. Means for controlling a plurality of double-acting pistons comprising in combination a pair of leading-off pipes for the two sides of each piston, inlet and exhaust valves arranged in pairs for each leading-off pipe, a set of two pairs of cams for each two pairs of valves, one cam of each pair having a 120 short valve-opening operating face and having a valve-closing dwell and the other cam of each pair having a long operating face providing a valve-opening dwell, the individual cams in each pair being set in opposi- 125 130

- tion to each other, and corresponding cams in the two pairs being set in corresponding operating positions, and means for operating said cams.
5. 2. Means for controlling a plurality of double-acting pistons comprising in combination a pair of leading-off pipes for the two sides of each piston, inlet and exhaust valves arranged in pairs for each leading-off pipe, a set of two pairs of cams for each two pairs of valves, one cam of each pair being peaked and the other having an extended and rounded lifting surface set in opposition to the peak of its companion, and means for revolving said cams.
10. 3. Means for controlling a plurality of double-acting pistons comprising in combination a pair of leading-off pipes for the two sides of each piston, inlet and exhaust valves arranged in pairs for each leading-off pipe, a set of two pairs of cams for each two pairs of valves, the two outer cams of each set of four being peaked and the companion of each being set in opposition thereto and having an extended rounded lifting surface, and means for revolving said cams.
15. 4. Means for controlling a plurality of double-acting pistons comprising in combination a pair of leading-off pipes for the two sides of each piston, inlet and exhaust valves arranged in pairs for each leading-off pipe, a set of two pairs of cams for each two pairs of valves, each set of four cams comprising two peaked and two rounded and extended cams set in opposition to said peaked cams and the extended cam surfaces in one set overlapping those in the next set, and means for revolving said cams.
20. 5. Means for controlling a plurality of double-acting pistons comprising in combination a pair of leading-off pipes for the two sides of each piston, inlet and exhaust valves arranged in pairs for each leading-off pipe, a set of two pairs of cams for each two pairs of valves, one cam of each pair being peaked and the other having an extended and rounded lifting surface set in opposition to the peak of its companion, and the cams being arranged to control inlet and exhaust valves alternately, and means for revolving said cams.
25. 6. Means for controlling a plurality of double-acting pistons comprising in combination a pair of leading-off pipes for the two sides of each piston, inlet and exhaust valves arranged in pairs for each leading-off pipe, a set of two pairs of cams for each two pairs of valves, one cam of each pair being peaked and the other having an extended and rounded lifting surface set in opposition to the peak of its companion, and the peaked cams in one set being set in opposition to those in the next set, and means for revolving said cams.
30. 7. Means for controlling the admission and exhaust of working fluids to and from engines operated thereby, comprising in combination a casing divided into two main chambers by a partition, valves located in one of said chambers, actuating means for said valves located in the other of said chambers, and operative connections traversing said partition for transmitting movement from and actuating means to said valves, said valve-actuating means comprising a set of short-faced cams and a set of long-faced cams.
35. 8. Means for controlling the admission and exhaust of working fluids to and from engines operated thereby, comprising in combination a casing divided into two main chambers by a partition, rotary cams in the other chamber and lifting stems controllable by said cams, attached to said valves and extending through said partition, said cams including short-faced cams and long-faced cams arranged in groups, the short-faced cams in one group being arranged in opposition to the long-faced cams in the same group and so as to correspond in operating position with the long-faced cams of another group, and means for concurrently operating all of said cams.
40. 9. Means for controlling the admission and exhaust of working fluids to and from engines operated thereby, comprising a casing having an unbroken longitudinal inlet chamber, a similar exhaust chamber and an intermediate chamber divided transversely into conduits, an inlet and an exhaust valve between each of said conduits and said inlet and exhaust chambers respectively, and means for actuating said valves in suitable order.
45. 10. Means for controlling the admission and exhaust of working fluids to and from engines operated thereby, comprising a casing having a space for valves and conduits, parallel longitudinal chambers within said space and on opposite sides thereof, inlet valves opening from one of said parallel chambers into the remaining space, corresponding exhaust valves opening from the other chamber into said remaining space, transverse partitions forming separate conduits into each of which opens one inlet and one exhaust valve, and means for opening and closing said valves in appropriate order.
50. 11. Means for controlling the admission and exhaust of working fluids to and from engines operated thereby, comprising a casing having parallel longitudinal chambers on different levels and opposite sides, conduits connecting the under side of one chamber with the top of the other, valves under one chamber and over the other in each conduit and means for opening and closing said valves in appropriate order.
55. 12. Means for controlling the admission and exhaust of working fluids to and from engines operated thereby, comprising a casing having parallel longitudinal chambers on different levels and opposite sides, valves under one chamber and over the other in each conduit and means for opening and closing said valves in appropriate order.

and exhaust of working fluids to and from engines operated thereby, comprising a casing having parallel longitudinal chambers on different levels and opposite sides, conduits connecting the under side of one chamber with the top of the other, valves under one chamber and over the other in each conduit said valves having parallel descending lifting stems, a rotary shaft beneath said stems, cams thereon corresponding to said stems, and pivotally mounted valve levers bearing on said cams and supporting said stems.

13. A fluid controlling device comprising a valve chamber having therein a series of pockets, a fluid-conveying conduit connected to each pocket, an inlet valve for each pocket, an exhaust valve for each pocket, and valve-operating means for opening and closing the inlet and exhaust valves for each pocket in alternate relation and adapted to cause one of these valves to dwell at the open position while the other is kept closed and to dwell at the closed position while the said other valve is both opened and closed.

14. The invention claimed in claim 13 in which the pockets are arranged in pairs and in which the valve-operating means are adapted to open or close the inlet valve of one of the pockets of a pair concurrently with the opening or closing of the exhaust valve of the other pocket of the same pair.

15. The invention claimed in claim 14 in which the valve-operating means comprise an equal number of short-faced and long-faced cams arranged in groups so that the short-faced cams in one group correspond in operating position with the long-faced cams in another group.

16. A fluid-controlling device comprising a valve chamber having an inlet passage extending from end to end thereof, an outlet passage likewise extending from end to end

of the valve chamber, and a series of pockets each communicating with the inlet passage 45 and with the outlet passage; a fluid-conveying conduit communicating with each pocket, a series of inlet valves controlling communication between the inlet passage and the respective pockets, a series of exhaust valves controlling communication between the respective pockets and the exhaust passage, and valve-operating means adapted to open and close the inlet and exhaust valves for each pocket in alternate relation. 55

17. The invention claimed in claim 16 in which the pockets are arranged in pairs and in which the valve-operating means comprise an equal number of short-faced and long-faced cams arranged in groups so that the short-faced cams in one group correspond in operating position with the long-faced cams in another group, and are adapted to open or close the inlet valve of one of the pockets of a pair concurrently with the opening or closing of the exhaust valve of the other pocket of the same pair, and the short-faced cams in one group being arranged in opposition to the long-faced cams in the same group. 70

18. A fluid-controlling device having, in combination, an inlet valve, an exhaust valve, and valve-operating means for opening and closing the inlet and exhaust valve in alternate relation and adapted to cause 75 one of these valves to dwell at the open position while the other is kept closed and to dwell at the closed position while the said other valve is both opened and closed.

In testimony whereof I have affixed my 80 signature.

GEORGE WALDEMAR BUNGAY.
